UNITED STATES PATENT OFFICE.

STEFANUS NIELSEN, OF NEW YORK, N. Y., ASSIGNOR TO THE MONARCH TYPEWRITER COMPANY, OF SYRACUSE, NEW YORK, A CORPORATION OF NEW YORK.

TYPE-WRITING MACHINE.

No. 889,954.

Specification of Letters Patent.

Patented June 9, 1908.

Application filed February 4, 1905. Serial No. 244,195.

To all whom it may concern:

Be it known that I, STEFANUS NIELSEN, subject of the King of Norway, and resident of the borough of Brooklyn, in the city of New York and State of New York, have invented certain new and useful Improvements in Type-Writing Machines, of which the following is a specification.

My invention relates more particularly to the ribbon mechanism of that class of type-writing machines employing a ribbon vibrator or carrier, by which term is meant any device for moving the ribbon to cover and uncover the printing point.

One object of my invention is to provide a construction wherein a ribbon having a plurality of fields of different characteristics may, at a printing operation, be moved to cover the printing point with any desired field of the ribbon.

Another object is to provide means to dispense at will with the crosswise feed of the ribbon in that class of machines employing a ribbon vibrator and wherein the ribbon has both a crosswise and a lengthwise feed.

A further object is to provide means to enable a ribbon of more than one color to be employed in the last named class of machines.

Other objects will subsequently appear.

To the above ends the invention resides in the features of construction, combinations of devices and arrangements of parts to be hereinafter more fully described and particularly pointed out in the appended claims.

In the accompanying drawings, Figure 1 is a vertical front to rear sectional view, taken about centrally, of one form of typewriting machines embodying my invention. Fig. 2 is a fragmentary front elevation showing the upper portion of the machine. Fig. 3 is a rear view taken on a plane represented by the line *x* in Fig. 1, various parts being omitted. Fig. 4 is an enlarged fragmentary top plan view showing parts of the ribbon mechanism. Figs. 5 and 6 are views similar to Fig. 4 but showing various parts in different positions from those in which they appear in said Fig. 4.

My invention is shown as embodied in a Monarch typewriting machine but it may be adapted to other forms of writing machines.

In the drawings, 1 is the base of the machine supporting corner posts 2, which sustain a top plate 3. Key levers 4 are ful-

crumed on a fulcrum plate 5 and each key lever is provided with a restoring spring 6. Pivoted at 7 to each key lever is a sub-lever 8, the lower portion whereof co-acts with a fixed abutment 9 and the upper portion 60 whereof is connected by a link 10 with a type bar 11 which is one of a segmentally arranged series. Each type bar 11 is seated in a radial slot 12 formed in a segmental type bar support 13, the heels of the type bars being perforated to receive a segmental pivot wire 14 which is contained in a groove cut in the top face of the segmental support 13. Instead of this mode of pivoting the type bars on a fulcrum wire they may be provided with 70 separate hangers and pivots. The type bars are normally supported at their free ends by a segmental type rest 15 and said bars are adapted to coöperate with a platen 16 mounted in a carriage 17, said carriage being 75 guided and supported by anti-friction balls 18 which are seated in grooved rails 19 on the carriage and in oppositely grooved rails 20 mounted on brackets 21 which are fixedly secured to the top plate 3. The carriage 17 80 is provided with a feed rack 22 which normally meshes with a pinion 23, the latter being operatively connected with an escapement wheel 24.

Adapted to coöperate with the escapement 85 wheel are feed dogs 25 mounted on a pivoted dog rocker 26 which has a horizontal arm 27 connected by a rod or link 28 with the rearwardly extending arm 29 of a universal bar frame 30 pivoted in the base of the machine 90 at 31 (Fig. 3). The frame 30 carries a universal bar 32 which extends from side to side of the machine beneath the spacing levers (not shown) and the series of key levers 4, and is adapted to be actuated by said levers 95 when the latter are depressed as happens during each printing or spacing operation. The carriage 17 is connected by a strap 33 with a spring drum 34 which tends to draw the carriage to the left so that when the universal bar 32 is actuated the escapement mechanism just described is caused to be operated in a known manner and thereby to permit of letter space movements of the carriage.

Ribbon spools 35 arranged above the top plate 3 at each side of the machine and forwardly of the platen, receive a ribbon 36, which, as herein shown, is divided longitudinally into fields *a* and *b* of different charac- 110

teristics, that is to say, the field *a* may be of one color such as black, and the field *b* of another and different color such as red, or the field *a* may be copying ribbon and the field *b* record ribbon, etc. The ribbon 36 may be fed longitudinally from either spool to the other by any suitable means.

The drawings illustrate a ribbon feed mechanism which is similar to that employed in the Monarch typewriting machine and which is explained in U. S. Patent to Jacob Felbel & Carl Gabrielson No. 703,339, dated June 24, 1902. Each ribbon spool 35 is carried by and moved with an upright shaft 37 which rotates in a fixed bearing 38 and has secured at its lower end a small beveled gear 39. The gear 39 meshes with a beveled pinion 40 secured to the forward end of a horizontal shaft 41, which shaft carries at its rear end a beveled pinion 42 which is adapted to mesh with a beveled driving pinion 43 mounted on a driving or power shaft 44. Rotary movement is transmitted to the shaft 44 by beveled pinions 45 and 46, the pinion 45 being operationally connected with the driving shaft and the pinion 46 being so connected with the spring drum 34 as to rotate with the latter only during the movement of the carriage 17 in letter space direction. It will be understood that both ribbon spools are connected with similar gear trains which are adapted to be actuated from driving pinions 43 on the driving shaft 44. As explained in the above cited patent the driving or power shaft 44 is capable of longitudinal movement, and it is further to be understood that the longitudinal position of said shaft determines which driving pinion 43 will be in mesh with its co-operating pinion 42 and which ribbon spool will be turned to wind the ribbon thereon. Midway between the ribbon spools the ribbon 36 is threaded through a ribbon vibrator or carrier 47, the lower end whereof is provided with a vertical slot 48 and is shouldered off at 49. A loop 50 is secured at the rear of the lower portion of the vibrator. The vibrator 47 is guided and supported in the upright arms 51 of the supporting bracket 52, the latter being secured to the top plate by screws 53. Secured to the under side of the top plate in rear of the bracket 52 is a downwardly depending lug 54 which is formed with a pair of rearwardly and downwardly projecting ears 55. An operating lever 56 is pivotally secured at 57 in the lug 54 and the forward end of said operating lever is adapted to play in the slot 48 in the ribbon vibrator and said forward end is provided with a cross pin 58 which engages with the loop 50 at the rear of said vibrator. A restoring spring 59 vertically disposed at the rear of the ribbon vibrator has one end secured to the latter and the other end secured in the forward end of the operating lever 56. The rear arm of the operating lever is

formed with an elongated slot 60 with which engages a pin or stud 61 secured in the top of a link 62. The link is provided near its upper end with a downwardly and forwardly bent arm 63 and at its lower end said link is pivoted at 64 to the rear arm 29 of the universal bar frame. The link is adapted to be swung about the pivot 64 in order to cause the stud 61 to move longitudinally of the slot 60 so as to engage the operating lever 56 at varying distances from the pivot 57 and thereby to vary the throw of the ribbon carrier or vibrator 47. The means employed to swing the link 62 in order to vary the throw of the ribbon comprises an eccentric controller designated as a whole by the numeral 65 which is slidably mounted upon the driving shaft 44 and which is normally adapted to co-operate with the strap formed by the link 62 and its bent arm 63. The eccentric controller 65 comprises a comparatively narrow eccentric working face 66, a tapered or cam portion 67 and a sleeve portion 68, which latter is formed with a circumferential groove or depression 69 (Fig. 3). A screw 70 passes into the sleeve portion 68 and enters an elongated groove or slot 71 in the power shaft 44. The eccentric member 65 is thereby slidably connected with the driving or power shaft 44 and is caused to rotate with said shaft, but may be moved longitudinally of said shaft without affecting the latter. The driving shaft 44 may also be moved longitudinally without affecting the member 65.

The longitudinal movement of the eccentric member 65 is controlled by a positioning or switching member or slide 72, which comprises first a vertically disposed arm 73, terminating at the top in a perforated collar portion 74 and at the lower end in a fork 75 which partially surrounds the depression 69 in the member 65, and second, a short obliquely disposed arm 76 (Fig. 1) terminating at its lower end in a fork 77. A pull and push rod 78 has its inner end fixedly secured in the collar portion 74 of the positioning member or slide 72 and bears in the flange of the top plate 3, passing through the latter and terminating exteriorly of the machine in a finger button 79. The rod 78 is formed with notches 80, 81 and 82 with which a locking spring 83 is adapted to engage, said locking spring being secured to the top plate by a screw 84. The rod 78 also has a bearing in a lug 85 depending from the top plate, which lug serves also as one of the bearings of the driving shaft 44.

The ears 55 of the lug 54 are perforated to permit of the passage of a horizontal rock shaft 86 which is slidably mounted in said ears, and, as viewed from the rear, terminate at the left end in a head 87. Just outside the left hand ear 55 (Fig. 4) the shaft 86 is embraced by the fork 77 of the arm 76. 130

Fixedly secured to the shaft 86 between the ears 55 is a rearwardly projecting lever arm 88 which terminates in a horizontally disposed lip or ledge 89. A forwardly projecting lever arm 90 terminates at its forward end in a hook portion 91, the two arms of which lie beneath the shoulders 49 of the vibrator 47, and at the rear in a collar portion 92 which is perforated so as to permit of the passage of the rock shaft 86, which latter serves as a pivotal support for the said forwardly projecting arm 90. A screw 93 is screwed into the collar portion 92 and enters an elongated slot 94 in the shaft 86. A coiled spring 95 surrounds the rock shaft 86 between the arm 88 and the collar portion 92 of the arm 90, and, as viewed from the rear of the machine, serves normally to maintain the arm 90 against the inner face of the left hand ear 55 and the arm 88 against the inner face of the right hand ear.

Depending from the under side of the top plate is a lug 96 to which is secured one end of a restoring spring 97, the other end whereof is attached to the link 62. The spring 97 constantly tends to draw the pin 61 to the rear of the slot 60.

If a one-color ribbon is in use and it be desired to employ a two-color ribbon, the latter may be substituted in a known manner. With the two-color ribbon in place and the parts positioned as shown in Figs. 3 and 4, the ribbon will be fed progressively crosswise during successive printing operations and some of the type impressions will be made upon the field *a*, which may, for example, be black in color, some impressions will be made upon the field *b* which may, for example, be red in color, while yet other impressions will be made partly upon one field and partly on the other. By this mode of operation a variegated or parti-colored effect will be obtained which may be desirable in some styles of ornamental typewriting. In most forms of typewriting, however, it is desirable to print in one-color at a time. If, as suggested, the two-color ribbon be, as is most usual, a black and red ribbon and it be desired to print only on the black field, the pull rod 78 is drawn outward (or to the left as viewed in Figs. 3 to 6, inclusive) until the locking spring 83, which normally is in engagement with the first notch 80, engages with the second notch 81. As it moves outward the rod 78 carries with it the switching member or slide 72, which in turn, by means of the fork 75, draws the eccentric member 65 leftward so as to disengage the eccentric face 66 from the link 62 and its bent arm 63, whereupon the spring 97 draws the stud 61 towards the rear end of the slot 60. This leftward movement of the switching member 72 also brings the fork 77 into contact with the inner face of the head 87 of the rock shaft 86, but the latter is not caused to move

longitudinally thereby at this stage. The parts will be now in the position indicated in Fig. 5. The spring 97 maintains the link 62 at the furthest point possible from the fulcrum of the operating lever 56, so that during each printing operation the operating lever is thrown upward to the same height, and the parts are so adjusted that this upward movement causes the upper portion of the ribbon to cover the printing point 75 and the path of the type impressions will be in a straight line longitudinal of the ribbon field *a*, or the black field. If it be desired to print from the red field *b* of the ribbon, the pull rod 78 is drawn outward still further until the locking spring 83 engages with the third notch 82 in said rod. The outward movement of the rod 78 causes a further outward or leftward movement of the switching member 72 and the fork 77 of the latter being 80 now in contact with the head 87 of the rock shaft 86, causes a leftward longitudinal movement of said rock shaft in its bearings in the ears 55. The rear lever arm 88, which is fixedly secured to the rock shaft 86, participates in this longitudinal movement of the rock shaft 86 and is drawn bodily leftward, transversely of the lever 56, until the ledge or lip 89 at the rear of said lever arm 88 is vertically under the rear end of the operating lever 56. During this movement the rear lever arm 88 compresses the coiled spring 95 between the arm itself and the collar portion of the forward lever arm 90, which latter remains motionless during the 90 100 positioning of the parts just described. The various parts will now be in the positions indicated in Fig. 6.

At each printing operation, the rear arm of the operating lever 56 acts upon the lip or 105 ledge 89 and thereby causes the rear lever arm 88 to swing downwardly, rotating the rock shaft 86 in its bearings. The pin and slot connection between the rock shaft and the forward lever arm 90 causes the latter to 110 swing upward at the same time and its hooked portion 91 engaging with the shoulders 49 of the ribbon vibrator raises the latter upwardly. The parts are so adjusted that this upward movement or throw of the vibrator brings the lower portion of the ribbon to the printing point and the type impressions obtained by a repetition of the printing operation follow a path which is in a straight line longitudinal of the field *b*, that is, the red 115 field of the ribbon. It is apparent that the arms 88 and 90 form respectively the rear and forward arms of a second operating lever, the fulcrum whereof is the rock shaft 86, this fulcrum being nearer the point of application 120 of the power than is the fulcrum 57 of the first operating lever 56. The same length of movement of the power, that is the same downward movement of the link 62, causes a greater extent of movement at the forward 125 130

or lower end of the second lever than of the first lever 56. The result is that with the second operating lever inoperative, the ribbon vibrator is thrown upward to a less height than is the case when said second lever operates. The forward end of the second lever moves upward faster and goes higher than the corresponding part of the lever 56.

10 The elongated loop 50 and the pin 58 form a connection which enables the vibrator to be operated by the second lever without being interfered with by the slower moving first lever 56. When the second lever is inoperative and the vibrator is moved upward by lever 56 the shoulders 49 of the vibrator move upward away from the hooked portion 91 and the second operating lever remains motionless. Whether the vibrator is actuated by the lever 56 or by the second lever comprising the arms 88 and 90, in either case the light rest spring 59 restores the vibrator from printing to normal position. If it be desired to again print upon the black field of the ribbon the rod 78 is pushed in until the locking spring 93, disengaging from the notch or depression 82, again engages with the second notch 81. This causes the switch or slide 72 and the eccentric member 65 controlled thereby, to move inward or towards the right until they again attain the position indicated in Fig. 5, while at the same time the rock shaft 86, under the influence of the compressed restoring spring 95, is moved 35 longitudinally inward until said rock shaft is also restored to the position indicated in said Fig. 5. With the parts so positioned, the field *a* of the ribbon, that is the black field, is moved to the printing point at each printing 40 operation as hereinbefore explained. If the rod 78 be pushed further in until the locking spring 83 again engages with the first notch 80 in said rod, the parts will be restored to the positions indicated in Figs. 3 and 4, the tapered 45 or cam portion 67 of the eccentric member 65 effecting an easy and certain entrance into the space between the link 62 and its bent arm 63 and thereby causing the eccentric face 66 to again engage with its strap. The 50 various parts are now positioned so as to again cause a progressive crosswise feed of the ribbon as hereinbefore explained.

Various changes in the construction, arrangement and combination of the parts may 55 be effected without departing from the spirit of my invention.

What I claim as new and desire to secure by Letters Patent, is:—

1. In a typewriting machine, the combination of a ribbon vibrator, a lever connected thereto for operating the same, a link, means for actuating said link, means for maintaining said link in engagement with the operating lever at a fixed distance from the fulcrum 65 of the latter, and means separately connected

to said vibrator for altering the throw of said vibrator while said link is so maintained in engagement with the operating lever.

2. In a typewriting machine, the combination of a ribbon vibrator, a lever for operating the same, an universal bar, a link constantly connected with said universal bar and with said operating lever, a second operating lever normally disconnected from said link, and means for operatively connecting 75 said second operating lever with said link and thereby altering the throw of the ribbon vibrator.

3. In a typewriting machine, the combination of a ribbon vibrator, a pair of relatively 80 movable levers for operating the same, a link, and means for actuating the link, said link being adapted to operate one or both of said levers and thereby to throw the ribbon vibrator different distances. 85

4. In a typewriting machine, the combination of a ribbon vibrator, a plurality of relatively movable levers for operating the same, a link for actuating said levers, said link being constantly engaged with only one of 90 said levers, an universal bar connected with said link and adapted to move it, and printing key levers adapted to actuate said universal bar.

5. In a typewriting machine, the combination of a ribbon vibrator, a pair of relatively 95 movable levers for operating the same, said levers having different fulcrum points, a single means adapted to throw each of said levers a fixed distance, and means for causing 100 said single means to act upon one or simultaneously upon both of said levers to throw the ribbon vibrator different distances.

6. In a typewriting machine, the combination of a ribbon vibrator, a pair of relatively 105 movable levers for operating the same, a key actuated universal bar, and a link connected with said universal bar and operative upon one of and movable by said levers at one time to throw said vibrator a predetermined 110 distance and operative upon the other of said levers at another time to throw said vibrator a different predetermined distance. 115

7. In a typewriting machine, the combination of a ribbon vibrator, a pair of relatively 115 movable levers for operating the same, a key actuated universal bar, a single link connected with said universal bar and operative upon one of said levers to throw said vibrator a predetermined distance and operative upon 120 the other of said levers to throw said vibrator a different predetermined distance, and hand actuated means for bringing said last named lever into operative relation with said link.

8. In a typewriting machine, the combination of a ribbon vibrator, two relatively movable levers for operating the same, a link, means for causing said link to operate on one of said levers at progressively varying distances from the fulcrum of said lever, means 125 130 135

for actuating said link to cause it to vibrate said lever on its fulcrum, means for throwing out of operative relation the means for moving said link progressively, and means for bringing the second operating lever into operative position to be vibrated by said link.

9. In a typewriting machine, the combination of a ribbon vibrator, a slotted lever adapted to operate the same, a link provided with a pin adapted to move back and forth in the slot of said lever, an eccentric adapted to coöperate with said link and thereby to control said movement, a second vibrator-operating lever, and means adapted to disconnect the eccentric from the link and to connect the second named operating lever with said link.

10. In a typewriting machine, the combination of a ribbon vibrator, a pair of relatively movable levers adapted to operate said vibrator, a single means for actuating said levers to throw said vibrator different distances, a crosswise ribbon feed mechanism operative in connection with said single means, and hand actuated means whereby the crosswise ribbon feed mechanism is rendered inoperative and thereafter one of said levers is brought into operative relation with said single means, the other of said levers being in constant engagement with said single means.

11. In a typewriting machine, the combination of a ribbon vibrator, a pair of relatively movable operating levers therefor, a single link for actuating said levers, an arm of one of said levers being adapted to be moved transversely of said link for alternative connection with and disconnection therefrom, an universal bar connected with said link, and printing key levers adapted to actuate said universal bar.

12. In a typewriting machine, the combination of a ribbon vibrator, a pair of relatively movable operating levers therefor, a link for actuating said levers, one of said levers being adapted to be moved transversely of said link for alternative connection with and disconnection therefrom, a crosswise ribbon feed mechanism connected with said link, and hand operated means adapted to throw out of operation said crosswise ribbon feed mechanism and thereafter to bring into operation said transversely movable lever.

13. In a typewriting machine, the combination of a ribbon vibrator, a pair of relatively movable levers for throwing said vibrator different distances, a single link for actuating said levers, a slide adapted to operatively connect or disconnect said link with one or simultaneously with both of said levers, and means controlled exteriorly of the machine for actuating said slide.

14. In a typewriting machine, the combi-

nation of a ribbon vibrator, a pair of levers for throwing said vibrator different distances, a single link for operating said levers, said link having a strap, a power shaft, an eccentric adapted to slide on said shaft, a switching member adapted to move said eccentric, and devices carried by said member and adapted to control one of said levers, and means for controlling said member.

15. In a typewriting machine, the combination of a ribbon vibrator, a lever for operating the same, an universal bar, a link connected with said universal bar and with said operating lever, and a second operating lever movable relatively to the first named operating lever but adapted to be operated by the first named operating lever and thereby to alter the throw of the ribbon vibrator.

16. In a typewriting machine, the combination of a ribbon vibrator, a pair of relatively movable operating levers therefor, the relative positions of the arms of one of said levers being capable of alteration, means for altering the relation between the arms of said lever whereby said lever is brought into operative relation with the other operating lever, and means for actuating said last named lever.

17. In a typewriting machine, the combination of a ribbon vibrator, a pair of relatively movable operating levers therefor, the power arm of one of said levers being movable transversely of the other lever, means for actuating said last named lever, and means for causing a transverse movement of said power arm so as to cause the lever of which it is a part to be actuated by the other lever.

18. In a typewriting machine, the combination of a ribbon vibrator, a pair of operating levers therefor, one of said levers having a power arm movable transversely of the other lever, a single link for operating said levers, said link having a strap, a driving shaft, an eccentric adapted to slide on said shaft, a switching member adapted to move said eccentric, devices carried by said switching member and adapted to control said transversely movable power arm whereby the lever of which said power arm is a part is brought into and out of operative relation with the other lever, and means for controlling said switching member.

19. In a typewriting machine, the combination of a ribbon vibrator, an operating two-part lever for said ribbon vibrator, means for actuating said operating lever, and means for moving one part of said lever into and out of position to be actuated by said actuating means.

20. In a typewriting machine, the combination of a ribbon vibrator, an operating two-part lever for said ribbon vibrator, and means for moving one part of said lever into

and out of position to operate said ribbon vibrator.

21. In a typewriting machine, the combination of a ribbon vibrator and a two-part 5 operating lever therefor, one of the parts of said lever being movable relatively to the other into and out of operative position.

22. In a typewriting machine, the combination of a ribbon vibrator, a rock shaft having an integral arm for operating said ribbon 10 vibrator, and means for rocking said rock shaft to operate said ribbon vibrator; said rock shaft being shiftable bodily with said arm to connect it with and to disconnect it 15 from its actuating means.

23. In a typewriting machine, the combination of a ribbon vibrator, means permanently connected thereto for moving said vibrator, a rock shaft having an integral 20 arm for operating said ribbon vibrator through said permanent means, means for rocking said rock shaft, and means for operatively connecting said rock shaft arm with or disconnecting it from its rocking means.

24. In a typewriting machine, the combination of a ribbon vibrator, two relatively 25 movable operating members, either of which is capable of operating said ribbon vibrator, said operating members having different extents of motion, and a returning spring connecting said ribbon vibrator with the operating member having the less extent of motion.

25. In a typewriting machine, the combination of a ribbon carrier, two relatively 35 movable operating levers connected therewith, means for enabling either one of said operating levers to move the ribbon carrier, an universal bar, and a single actuating device between said universal bar and said operating levers for actuating either of said levers at will.

26. In a typewriting machine, the combination of a ribbon carrier, two operating 45 members each connected directly to said ribbon carrier, each adapted to move the ribbon carrier a different distance, an actuating means connected permanently to one of said operating members, and means for connecting and disconnecting at will the other of said operating members with said actuating means.

27. In a typewriting machine, the combination of a ribbon carrier, a lever for throwing the same a given distance, means permanently connected with said lever for actuating it, a two-part lever also operatively connected with said ribbon carrier but normally disengaged from the first named operating lever, and means for moving one part of the two-part lever into operative engagement with the other operating lever whereby the ribbon carrier may be thrown a different given distance.

28. In a typewriting machine, the combination of a ribbon vibrator, a lever for throwing the same, means for actuating said lever, a second lever for also throwing said vibrator but to a different extent, said second lever comprising two parts, one movable relatively to the other and to the first named lever, a rock shaft upon which one part of said two-part lever is fixed, a sliding connection between said rock shaft and the other part of said two-part lever, means for sliding said rock shaft endwise, and a spring for returning said rock shaft endwise.

29. In a ribbon vibrating mechanism, a pair of relatively movable operating levers having their fulera located at different distances from the vibrator and adapted to move the ribbon different distances for changing the throw of the vibrator.

30. In a typewriting machine, the combination with a set of printing key levers, of a ribbon vibrating mechanism comprising a pair of operating levers having their fulera located at different distances from the ribbon vibrator and adapted to move the ribbon different distances, both said levers being operative by each of said key levers.

31. In a ribbon vibrating mechanism, the combination of a pair of relatively movable operating levers, and means for actuating said levers, said means being adapted either to operate one of said levers singly or both of said levers at the same time and thereby to vibrate the ribbon different distances.

32. In a typewriting machine and in a ribbon vibrating mechanism, the combination of a plurality of relatively movable operating levers, a key-actuated universal bar, and a constant connection between one of said operating levers and said universal bar, another of said operating levers being adapted at will to be operated by the first named lever when the universal bar is actuated.

33. In a typewriting machine and in a ribbon vibrating mechanism, the combination of a pair of relatively movable levers operative to vibrate the ribbon, said levers having different fulerum points, a single means adapted to throw each of said levers a fixed distance, and means for causing said single means either to act upon one or simultaneously upon both of said levers to vibrate the ribbon different distances.

34. In a typewriting machine, the combination of a ribbon vibrator, a lever for operating the same, a universal bar, means connecting said universal bar with the operating lever, and a second operating lever movable relatively to the first named operating lever but adapted to be operated by the first named operating lever and thereby to alter the throw of the ribbon vibrator.

35. In a typewriting machine, the combination of key levers, a ribbon vibrator, actu-

ating devices for the vibrator, a pair of operating levers, and hand-controlled means for varying the normal relation between said vibrator and said operating levers to change the throw of the vibrator when the key levers are actuated.

Signed at the borough of Manhattan, city

of New York, in the county of New York, and State of New York, this 3d day of February, A. D. 1905.

STEFANUS NIELSEN.
